DESIGN FOR A COSMETIC JAR OR THE LIKE

Elwood Whitney, New York, N. Y., assignor to Kathleen Mary Quinlan, Inc., New York, N. Y., a corporation of Delaware

Application January 10, 1933. Serial No. 46,781

Term of patent 14 years

To all whom it may concern:

Be it known that I, ELWOOD WHITNEY, a citizen of the United States, and a resident of the city, county and State of New York, have invented a new, original, and ornamental Design for Cosmetic Jar or the like, of which the following is a specification, reference being had to the accompanying drawing, forming part thereof.

In the drawing my design is shown in Figure

1 in elevation and in Figure 2 in top plan view.

The design comprises the shape of the jar as shown, and also the surface ornamentation of the top as shown in Figure 2.

I claim:

The ornamental design for a cosmetic jar or the like as shown and described.

ELWOOD WHITNEY.
